WALTER A. ROSELLE, OF NEW YORK, N. Y.

VALVE CONSTRUCTION FOR CONTAINERS

Application filed October 30, 1931. Serial No. 572,098.

My invention relates to means for controlling the outlet of collapsible tubes and other containers or receptacles for liquid and plastic materials, including paints, 5 tooth pastes, etc., as well as liquids.

One object of my invention is to provide a simple, inexpensive and reliable valve which can be readily operated.

A special object is to provide a construction adapted to small containers and which can be operated by the fingers of the same hand which holds the container.

In carrying out the invention, I provide a valve formed of flexible material mounted 15 in a housing in such a manner that the valve can be operated by the thumb or finger. The construction contemplates an inner portion constituting the neck of the container and having a curved outer end provided with an orifice, a flexible valve strip 20 slidable over the curved end for opening and closing the orifice and an outer housing.

In the drawing I have shown several 25 modifications of the construction, the method of operation of which will be understood from the following specification.

Fig. 1 is a plan or end view of a container having one form of my invention applied thereto.

Fig. 2 is a side view and partial section 30 showing the valve in the closed position.

Fig. 3 is a plan or end view of the interior member or neck.

Fig. 4 is a perspective view of the neck or 35 end member.

Fig. 5 is a detail view of one form of a flexible sliding valve strip employed in the construction illustrated in Figs. 1 and 2.

Fig. 6 is a plan view of another form of 40 device embodying my invention.

Fig. 7 is a longitudinal sectional view of the same showing the valve in the closed position and showing in dotted lines a knob 45 in the open position of the valve.

Fig. 8 is a perspective view of the valve strip employed in the form of device shown in Figs. 6 and 7.

Fig. 9 is a perspective view of another 50 form of valve strip.

Fig. 10 is a detail view showing a valve strip having another form of orifice.

The body 15 of the container may be of any type although the invention is especially applicable to collapsible tubes. This container has a projecting neck portion 16 which may be integral therewith or formed separately and suitably secured thereto in any suitable manner. This neck has a passage through it with an orifice 17 of any desired cross section. This orifice is controlled by a valve strip 18 formed of any suitable material which is flexible such for instance as sheet metal, celluloid or other tenacious substance. It should be understood, however, that the strip may have some degree of resiliency although this is not essential or preferred since the operation of the valve does not depend upon a spring action. I have found so-called German silver and soft stainless steel to be suitable metals from which to make the valve strip, but do not wish to be limited to these metals. The outer end of the neck is provided with semi-cylindrically curved bearing surfaces 19 on opposite sides of the orifice 17 for supporting the valve strip adjacent the orifice. The valve strip is provided with a projecting finger piece 20 which may be formed, for instance, by drawing a part of the metal of the strip so that the finger piece is integral with the strip. The edges of the strip are guided in a suitable manner, as for instance, by means of the flanges such as 21 on opposite sides.

The outer housing 22 encloses the valve strip and the neck and may be secured to the container or to the neck in any suitable manner, as for instance, by crimping the lower end of the housing as shown at 23. The outer end of the housing is provided with an outlet opening 24 in line with the orifice 17. The neck 16 may also have flanges 25 for guiding the end 26 of the valve strip.

In the form shown in Figs. 2 and 5, the valve strip is provided with an orifice 27 which is adapted to be brought into line with the orifices 17 and 24 in the open position of the valve. It will be seen that in

this case the edges 28 of the valve strip on opposite sides of the opening 27 are supported on the curved walls 19 so as to give added security and tightness to the closure.

5 It will be understood of course that the inner neck member 16 and the housing 22 are so constructed with respect to their adjacent surfaces as to leave just enough clearance between them for the movement of the 10 valve strip. This is to permit operation of the valve and at the same time provide as tight or close fitting a closure as possible or as may be considered desirable, having in mind the particular character of the 15 contents of the receptacle. The housing is provided with a slot 29 through which the finger piece 20 extends and in which the finger piece may be guided.

The housing may also be provided with 20 an outlet 30 if desired to permit escape of air or material as the valve is being closed. The housing has an outwardly flaring base 31 which serves in a measure to guard the finger piece 20 when the valve is open.

25 To open the valve it is simply necessary to pull down on the finger piece 20 whereby the valve will slide around the curved end of the neck member and open the passage to any desired extent. To close the valve it is simply necessary to press upwardly on the finger piece.

In the form of construction shown in Figs. 6 and 7 the inner member 35 is intended to be screwed on to the usual threaded neck of 25 the container and thus constitutes an extension of the neck. Obviously the form of construction shown in Figs. 1 to 4 might also have the neck member screw threaded for engagement with the container. The upper 40 end of the member 35 is provided with an outlet passage 36. The sides 37-37 are inclined somewhat so that the base of the closure device is wider than the outer end. The outer end of the neck member is provided 45 with a curved bearing surface 38 corresponding to the curved bearings 19 of Fig. 4 for the support of the flexible valve strip 39. This valve strip is provided with a finger piece 40 of any suitable form for operating the same. The housing 41 encloses the valve strip and the supporting member and is provided with a slot 43 in which the finger piece 40 may slide.

This valve strip is provided with a trans- 50 verse orifice 42 adapted to be brought into line with the outer end of the passage 36. The housing is provided with an orifice 45 which is normally closed. The base 44 of the housing may be secured to the inner 55 member 35 in any suitable manner. It will be understood that the inner and outer members will be spaced apart just sufficient to accommodate the flexible sliding valve strip in any suitable manner, as for instance, in 60 the same way as described with respect to

the device of Figs. 2, 3 and 4. This form of construction makes it possible to control a given size of opening with a shorter movement of the valve than with the form shown in Figs. 1 to 5, on account of the fact that the discharge orifice is transverse to the direction of movement of the strip instead of longitudinal of the movement of the strip. Obviously, however, the same size opening requires a wider strip when the form shown in Figs. 6 to 8 is employed. 75

It should be understood of course that the shape of the opening in the valve strip and in the neck and housing may be of any desired cross section. For instance, in Fig. 10 I have shown a circular opening 46. Furthermore certain advantages of the invention may be had without any opening in the valve strip as shown by the strip 47 in Fig. 9. Such a strip may in fact be made considerably shorter than the perforate strips, although in the case of the unperforated strip the advantage of support on opposite sides of the orifice when the valve is open is not attained. 85

The inner or neck member and the outer housing may be made of metal or molded composition but should preferably be made of or coated with material which will not rust or be corroded by the contents of the container. The valve strip should also be made of or coated with material which will not corrode under the conditions in which it is used. 90

The flexible valve strip being very thin 100 serves to provide a sharp and clean cut-off so as to avoid clogging up the device. It should be understood that the outer or discharge orifices such as 24 and 45 may be initially sealed in any suitable manner so as to give additional protection against evaporation. For normal use, however, the valve is sufficiently tight for all practical purposes. 105

It will be seen from the foregoing that 110 the valve may be opened and closed by the thumb of one hand while holding the container thus greatly facilitating the use of the container whether it be for liquid or paste. When the invention is applied to a 115 collapsible tube it is simply necessary to move the valve with the thumb while compressing the tube with the fingers of the same hand. In my former application #558,477 filed August 21, 1931, and now 120 matured into Patent No. 1,851,065, I have shown another form of my invention embodying the use of two finger pieces for operating the slide valve and it should be understood that the present construction 125 might be provided with two finger pieces if desired.

Other changes in details of construction 130 may be made without departing from the spirit or scope of my invention.

I claim:

1. A closure device comprising a neck having a cylindrical bearing surface at its outer end and a discharge passage, a flexible valve strip supported on said neck and slideable over said surface and provided with a single finger piece at one side of the neck and a housing enclosing said parts and provided with a discharge orifice registering 70 with the discharge passage in the neck, said neck and housing having guiding means for said strip and said housing having means of access to said finger piece.
2. A closure device comprising a neck 15 having a semi-cylindrical bearing surface at its outer end with lateral guide grooves and a discharge passage at the end, a flexible valve strip supported on said neck and slideable in said grooves and over said surface and provided with an operating finger piece at one side and a housing enclosing 20 said valve strip and provided with a discharge orifice registering with the discharge passage in the end of the neck and having 25 means of access to the valve strip.
3. A closure device comprising a neck having a semi-cylindrical bearing surface at its outer end, a discharge passage and inclined sides leading to said end, a flexible 30 valve strip supported on said neck and slideable over said sides and end surface and provided with a finger piece and a housing enclosing said neck and strip, and provided with a discharge orifice registering with the 35 discharge passage in the end of the neck and having means of access to the valve strip.
4. A collapsible tube closure having a projecting neck with oppositely disposed 40 guide walls and a connecting semi-cylindrical bearing end with an outlet, a flexible valve strip supported by and movable on said walls and end between the guide walls to control said outlet, and a housing enclosing 45 said strip and guiding one surface thereof, said housing having means of access to at least one end of said strip to permit actuation thereof, said housing having an outlet registering with the outlet in the neck.
5. A collapsible tube closure comprising a member having inclined side walls and a connecting semi-cylindrical bearing surface with an outlet therein, a flexible valve strip supported by and movable along said walls 55 and surface, and a housing having an orifice registering with said outlet and having means of access to the valve strip for actuating the same.
6. A closure device for a container comprising an inner member having a longitudinal passage, oppositely disposed external bearing surfaces and a connecting semi-cylindrical bearing surface at its end, a flexible valve strip slidably supported on said surfaces and having an integral projecting 60
- boss constituting a finger piece and a housing enclosing said strip and having a guide slot for said finger piece and having an orifice in line with the passage in the inner member.
7. A closure device having a projecting neck with oppositely disposed guide walls and a connecting semi-cylindrical bearing end and a discharge orifice in said end, a flexible valve strip supported by and movable on said walls and end and having a projecting finger piece, a housing enclosing said strip, said housing having means of access to at least one end of said strip to 75 permit actuation thereof and having a base extending beyond the finger piece and means on the neck and in the housing for guiding the flexible valve strip, said housing having a discharge opening registering with the discharge orifice in the end of the neck.
8. A closure device comprising a member having a passage with an outlet, inclined side walls and a semi-cylindrical bearing surface on each side of said outlet, a valve strip supported by and movable along said walls and surface and a housing having an orifice registering with the outlet in said member and having means of access to the valve strip for actuating the same.
9. A closure device for a container comprising an inner member having a longitudinal passage, oppositely disposed external inclined bearing surfaces and connecting semi-cylindrical bearing surfaces at its end, a flexible valve strip slidably supported on 90 said surfaces and having a projecting finger piece and a housing enclosing said strip and having a guide slot for said finger piece and having an orifice in line with the passage in the inner member.
10. A closure device having a projecting neck with oppositely disposed guide walls and a semi-cylindrical bearing end, a flexible valve strip supported by and movable on said walls and end, a housing enclosing 100 said strip, said neck and said housing having registering passages, said housing having means of access to at least one end of said strip to permit actuation thereof and having a relief outlet opposite said means 105 of access.
11. A tube closure comprising a member having a longitudinal passage, inclined side walls and a connecting semi-cylindrical bearing surface, a flexible valve strip supported by and movable along said walls and surface, and a housing having an orifice registering with the passage in said member and having a relief outlet at one side, said housing also having means of access 120 to the valve strip for actuating the same.
12. A closure device for a container comprising an inner member having a passage, oppositely disposed external bearing surfaces and a semi-cylindrical bearing surface 125

with an outlet at its end, a flexible metallic valve strip slidably supported on said surfaces and having an integral projecting boss formed by punching or drawing the metal 5 and constituting a finger piece, and a housing enclosing and guiding said strip, said housing having a discharge orifice registering with said outlet and said housing being provided with means to permit access to the 10 valve strip for actuating the same.

13. As an article of manufacture, a valve device for a tube closure, formed of a strip of thin, flexible, non-corrodible metal substantially non-resilient and provided with 15 an integral boss-like finger piece near one end drawn from the metal of the strip.
